UNITED STATES PATENT OFFICE.

ROMAN HENRY HEYN AND FRIDOLIN POLZER, OF NORWALK, CONNECTICUT.

STAPLING MACHINE.

Application filed May 7, 1923. Serial No. 637,214.

To all whom it may concern:

Be it known that we, ROMAN HENRY HEYN and FRIDOLIN POLZER, both citizens of the United States, and residents of Norwalk, county of Fairfield, and State of Connecticut, have invented certain new and useful Improvements in Stapling Machines, of which the following is a specification.

Our invention relates to an improvement 10 in stapling machines adapted for driving pre-formed staples and clinching the same. An object of our invention is the provision of a machine of this character which is capable of being very quickly assembled or 15 taken down as the case may be, thereby simplifying manufacture and facilitating the making of repairs, adjustments and renewals.

In the accompanying drawings,—
20 Fig. 1 is a sectional side elevation of a machine embodying our improvements;

Fig. 2 is a section on the line 2—2 of Fig. 1;

Fig. 3 is a section taken substantially on the line 3—3 of Fig. 1;

Fig. 4 shows the machine of Fig. 1 in perspective; and

Fig. 5 shows the machine taken down.

Referring to the drawings in detail,—1
10 designates the housing of the machine within which the various parts of the machine, such as the feeding mechanism, plunger and straightener, etc. are mounted. The housing is pivotally and removably mounted
25 upon a base 2, being secured thereto by a screw 3 passing through ears 4 on the base and the end of a slide or cutting bar 5 which is detachably secured to the housing by two screws 6 and 7 passing through the holes 8 and 9 in the cutter bar and holes 10 and 11 in the housing.

The cutter bar is provided at each side with laterally extending portions or flanges 12 for a purpose to be referred to herein-after.

The housing 1 is provided adjacent its forward end with a vertically extending guideway or channel formed as indicated at 13 and 14 so as to receive and guide a plunger
50 15 and its side flanges 16. The rear face of the plunger is provided with a cam lug 17 which is adapted to strike a removable pin 18 by which the upward movement of the plunger is limited. This pin or stop as just
55 pointed out is removable to permit of withdrawing of the plunger entirely from the

housing. The upper end of the plunger carries a cap or hand piece 19 by which the plunger is operated.

The housing 1 is also provided with a vertically extending guideway 20 which lies beside the guideways 13 and 14 for the plunger, this guideway receiving a staple straightener 21 which lies beside and is adapted to move parallel with the plunger 60 15. The straightener is provided with legs 22 and 23 which straddle the cam lug 17, and the forward end of the cutter bar 5, the straightener when moving downwardly 70 passing between the first staple 24 and the second staple 25 of the strip 26 to straighten the forward staple or prevent it from becoming bent as the case may be. The face of the legs of the straightener also function as a guide for the rear edge of the staple 24 after the same has been secured by the plunger and is traveling down the plunger guideway ahead of the plunger.

The upper end of the straightener is provided with flanges 27 and 28 extending at right angles to the face of the straightener these flanges lying against the edges or sides of the plunger, and with ears 29 and 30 projecting above the straightener. These ears 80 85 may be said to be a continuation or extension of the flanges 27 and 28, these flanges being given a reverse bend so to speak to provide a seat 31 for a short coil spring 32 which surrounds the plunger and whose upper end bears against the under side of 90 the cap or hand piece 19.

The plunger spring is designated 33 this spring surrounding both the plunger and straightener, its lower end bearing against the top of the housing 1 while its upper end 95 bears against the under side of the seat or reverse bend 31 of the straightener.

The housing 1 is provided with a sight opening 34 in the front thereof through which the operation of the machine may be 100 observed and with slots 35 in register with each other for cleaning the machine should the staple be bent so as to prevent movement of the same.

The cutter bar 5 which we have already 105 referred to is provided with a bevelled portion 36 at its forward end to provide a cutting edge 37 and with a cut-away portion 38 the latter permitting of a staple which is abnormally bent to fall down between the cutter bar and the housing and out through the bottom of the latter.

Supported within the housing 1 and removably secured thereto is a shell or housing comprising side members 39 and 40. The side member 39 is provided with a pair of pins 41 which pass through the holes 42 in the cutter bar and holes 43 in the side member 40 of the shell. The pins 41 as just pointed out hold the cutter bar in the shell, and the shell itself together with the cutter bar will be held in the housing 1 by the screws 6 and 7 already referred to. The side members 39 and 40 are also provided with openings 44 and 45 which register with the openings 35 already referred to in the housing.

Removably and pivotally mounted on a pin or stud 46 carried by the side member 39 is a hold-back lever 47 the forward end of which is adapted to rest upon the staple strip between the second staple 25 and third staple 48. The purpose of this hold-back is to prevent rearward movement of the staple strip when the feeder pawl 49 is moving rearwardly to staple-feeding position. The hold-back 47 is held down in operative position by a spring 50 provided with eyes 51 which slip over the pin 46.

The feeder pawl 49 is more or less of channel formation and is wide enough between its flanges to straddle the hold-back 47, as will be apparent from an inspection of Fig. 1. The forward end of the feeder pawl is provided with extensions 52 which engage behind the second staple 25 on the strip. The feeder pawl is pivotally mounted on one arm 53 of feeder cam 54, this cam being removably mounted on pin 54' supported in the side member 39. The feeder cam is provided with another arm 55 projecting into the path of the cam 17 the upper side of this arm being inclined or beveled to correspond with the inclined under side 56 of the cam 17. The feeder pawl 49 is held down in position by a small coil spring 56' between the under side of the lever arm 54 and the shoe, this spring being removably attached to the arm 54 by hooking the end of it through a hole in the arm for that purpose, and removably attached to the feeder pawl by a struck-up portion or prong 57 on the pawl. The cam lever 54 is held in the position shown in Fig. 1 by a coil spring 58 removably secured to the arm 53 by hooking it through a hole provided thereon for that purpose. The other end of the spring is supported by the reduced end of a small lug 59 provided with shoulders 60 against which the spring abuts. This lug is removably mounted on the pin 61 provided for that purpose in the side member 39.

In order that the staple strip may be withdrawn at any time if desired we provide a locking lever 62 pivotally and removably mounted on the pin 63, the face of this lever engaging the tail 64 of the hold-back lever.

By pressing downwardly on the end 65 of the locking lever the front end of the hold-back lever and feeder pawl may be raised clear of the staple strip to permit withdrawal of the same.

It will be seen from the foregoing that we have provided a stapling machine which may be readily assembled or taken down as the case may be. We may here mention that in assembling the shell composed of the side members 39 and 40 the pins on the side member 39 on which the operating parts are mounted serve to properly position the two side members as well as preventing their relative displacement in a plane transverse to the pins. In the side member 39 of the shell is an opening 66 and in the member 40 is an opening 67, these openings receiving the spring 58.

The operation of the machine is so obvious as to hardly require explanation.

With the machine assembled a strip of staples 26 may be pushed into the machine along the top of the cutter bar 5, until the forward staple strikes the side of the plunger guideway 13. The plunger and straightener are then pushed downwardly by striking the hand piece or cap 19, to straighten and sever the staple, the straightener also functioning to prevent turning or tipping of the staple not only during the severing operation but during the driving operation as well.

On the down motion of the plunger the cam 17 engages the arm 55 of the feeder cam 54 causing the latter to swing about its pivot carrying the feeder pawl 49 but not the hold-back rearwardly. Upon the up motion of the plunger the feeder pawl advances under the action of the spring 58 to feed the staple strip forward into position for the next severing and driving operation.

It is to be understood that the specific details of construction illustrated and described herein are illustrative rather than definitive and hence may be changed by those skilled in the art of stapling machines, within the purview of the invention.

We claim:

1. In a stapling machine, a housing, a shell removably mounted therein and a cutter bar spaced from the walls of said shell and removably supported thereby.

2. A stapling machine comprising a shell comprising two side members, a feeder cam, a feeder pawl and a hold-back lever within said shell, pins attached to one of said side members and carrying said feeder cam, pawl and hold-back, said pins serving to properly position the two side members and to prevent their relative displacement in a plane transverse to said pins.

3. In a stapling machine, the combination of a shell comprising two side members, a pin carried by one of said side members, a

hold-back lever pivotally and removably mounted on said pin, a second pin carried by one of said side members, a feeder cam pivotally and removably mounted thereon, 5 and a feeder pawl of channel formation pivotally attached to said feeder cam, the flanges of said pawl straddling said hold-back lever, the pivot pins supporting said hold-back lever and feeder cam, properly 10 positioning the side members of the shell and preventing their relative displacement in a plane transverse to said pins.

4. In a stapling machine, the combination of a shell, a hold-back lever, a feeder pawl 15 and a feeder cam pivotally mounted therein and removable therefrom, pins for properly positioning the two side members of the shell and preventing their relative displacement in a plane transverse to said pins and 20 a spring cooperating with said feeder cam, each of said side members being provided with an opening for receiving said spring.

5. In a stapling machine, the combination of a shell comprising two side members, 25 a hold-back lever mounted within said shell, a pin carried by one of said side members for pivotally and removably supporting said hold-back lever, a feeder pawl within said shell cooperating with said hold-back 30 lever, a feeder cam, a spring detachably secured to said cam and cooperating therewith, a lug cooperating with said feeder cam spring, a pin on one of said side members for pivotally and removably supporting 35 said lug and a spring for maintaining said hold-back lever in operative position, said spring being provided intermediate its ends with eyes for receiving the hold-back supporting pin, one end of said hold-back 40 spring engaging said hold-back lever and the other end engaging the pin for supporting said lug.

6. In a stapling machine, the combination of a shell comprising two side members, 45 pins carried by one of said side members for properly positioning the two side members and preventing their relative displacement, a cutter bar, a hold-back lever, a feeder pawl and a feeder cam removably and pivotally mounted on said pins within said shell, a housing adapted to receive said shell and the said cutter bar, hold-back lever, feeder pawl and feeder cam as a unit and means for 50 removably securing said shell and its contained parts to said housing.

7. A stapling machine comprising a 55 housing, a shell within the housing and a cutter bar, a hold-back lever, a feeder pawl,

a feeder cam and a locking lever for the hold-back lever mounted within said shell 60 and removable therewith from the housing as a unit.

8. A stapling machine comprising a housing, a hold-back lever, a feeder pawl and a feeder cam mounted in said housing, a 65 plunger and straightener co-operating with said first named mechanism, and a shell within said housing and carrying said feeder pawl and feeder cam, said shell and the pawl and feeder cam being removable from 70 the housing as a unit, and said plunger and straightener being mounted in said housing and removable therefrom as a unit.

9. A stapling machine comprising a housing, a cutter bar, a hold-back lever, a feeder 75 pawl, a feeder cam, and a shell mounted in said housing and carrying said cutter bar, hold-back lever, feeder pawl and feeder cam, said shell and the mechanism carried thereby being removable from the housing as a unit, 80 a plunger and a straightener mounted within said housing, a plunger spring and straightener spring co-operating with said plunger and straightener, and said plunger and straightener and said springs being removable 85 from said housing as a unit.

10. A stapling machine comprising a housing provided with vertically extending guideways, a flanged plunger and a straightener mounted in said guideways and vertically movable therein, a cap carried by said plunger, a spring surrounding said plunger and straightener and adapted to engage the said straightener and the upper part of said housing, a second spring surrounding said 95 plunger and adapted to engage the upper part of said straightener and the under side of said cap, a cam carried by said plunger, a removable stop carried by said housing and cooperating with said cam to limit the 100 upward movement of said plunger, said plunger, straightener and springs being removable from said housing as a unit, a shell mounted within said housing, a cutter bar, a hold-back lever, a feeder pawl and a 105 feeder cam pivotally mounted in said shell and removable from said housing with the shell as a unit, said feeder cam cooperating with the cam carried by said plunger.

This specification signed this 3rd day of 110 May, 1923.

ROMAN HENRY HEYN.

This specification signed this 4th day of May, 1923.

FRIDOLIN POLZER.
